TIME TEACHING AID

John J. Doherty, 306 N. Concord Ave.,
Fullerton, Calif. 92631

Filed Dec. 19, 1973, Ser. No. 426,322

Term of patent 14 years

Int. Cl. D19—07

U.S. Cl. D19—64

Fig. 1

Fig. 2

Fig. 3

Fig. 5

Fig. 4

FIG. 1 is a front view of a time teaching aid embodying my new design.

FIG. 2 is a side elevational view of the time teaching aid of FIG. 1.

FIG. 3 is a top view of the time teaching aid of FIG. 1.

FIG. 4 is a rear elevational view of the time teaching aid of FIG. 1.

FIG. 5 is an enlarged view of a portion of FIG. 1 to better illustrate the indicia in the portion illustrated.

I claim:

The ornamental design for a time teaching aid, as shown and described.
